(57) **CLAIM**

The ornamental design for a linear actuator, as shown and described.

DESCRIPTION

FIG. 1 is a first perspective view of a linear actuator showing my new and ornamental design,

FIG. 2 is a second perspective view thereof,

FIG. 3 is a front view thereof,

FIG. 4 is a first side view thereof,

FIG. 5 is a rear view thereof,

FIG. 6 is a second, opposite side view thereof,

FIG. 7 is a first end view thereof, and

FIG. 8 is a second, opposite end view thereof,

FIG. 9 is another first perspective view showing an alternate condition of use,

FIG. 10 is a second perspective view thereof,

FIG. 11 is a front view thereof,

FIG. 12 is a first side view thereof,

FIG. 13 is a rear view thereof,

FIG. 14 is a second, opposite side view thereof,

FIG. 15 is a first end view thereof, and

FIG. 16 is a second, opposite end view thereof,

FIG. 17 is another first perspective view showing an alternate condition of use,

FIG. 18 is a second perspective view thereof,

FIG. 19 is a front view thereof,

FIG. 20 is a first side view thereof,

FIG. 21 is a rear view thereof,

FIG. 22 is a second, opposite side view thereof,

FIG. 23 is a first end view thereof; and,

FIG. 24 is a second, opposite end view thereof.

1 Claim, 12 Drawing Sheets
